UNITED STATES PATENT OFFICE.

EDWARD F. WILKINSON, OF GRAMERCY, LOUISIANA.

DISMANTLING-TOOL.

1,311,029.

Specification of Letters Patent.

Patented July 22, 1919.

Application filed April 1, 1919. Serial No. 286,688.

To all whom it may concern:

Be it known that I, EDWARD F. WILKINSON, a citizen of the United States, residing at Gramercy, in the parish of St. James and 5 State of Louisiana, have invented certain new and useful Improvements in Dismantling-Tools; and I do hereby declare the following to be a full, clear, and exact description of the invention, such as will enable 10 others skilled in the art to which it appertains to make and use the same.

The present invention relates to improvements in dismantling tools for use in tearing down woodwork construction, and is intended to be particularly useful in the 15 dismemberment of tongue and groove boards forming floor, ceiling and wall construction.

It is an object of the present invention to provide a tool of this character which will 20 be susceptible of a variety of adjustments to accommodate the same to varying sizes of woodwork construction, and to enable a workman to make the necessary adjustments in a quick and easy manner.

25 A further object of the present invention resides in providing a compound tool which embodies in a relatively small and compact instrument a variety of tools heretofore made and used separately and capable of 30 performing all the work necessary to the dismantling of woodwork construction.

The invention will be more fully understood after reference to the accompanying drawings, in which like parts are indicated 35 by similar reference symbols throughout the several views, and in which:—

Figure 1 is an elevational view of an improved dismantling tool constructed in accordance with the present invention.

40 Fig. 2 is an enlarged elevational view, with parts shown in section, of the same, with an extension handle applied thereto.

Fig. 3 is a cross sectional view taken on the line 3—3 in Fig. 1.

45 Fig. 4 is a similar sectional view taken on the line 4—4 in Fig. 1; and

Fig. 5 is a transverse sectional view taken on the line 5—5 in Fig. 3.

Referring now more particularly to the 50 drawings, 1 designates the shank of the improved dismantling tool, being formed at one end with a nail extracting claw 2 and with a chisel edge 3 at its opposite end.

A lower foot 4 is connected to a sleeve 5, 55 which may be slidable on the shank 1 to admit of adjustment, or may be made fixed

with respect to the shank 1, as may be desired. As shown in Fig. 2, a spline 6 is received into a groove 7 in the sleeve 5, which permits of this vertical adjustment of the 60 sleeve and lower foot 4, while at the same time preventing the rotation of the sleeve on the shank.

A brace 8 connects the lower end of the sleeve 5 with the outer end of the lower foot 65 4, in order to support the latter where the most strain is received thereon. At its other end the lower foot 4 is formed into a nail extracting claw 9 for use where the claw 2 is not so applicable, as hereinafter set forth. 70

Above the lower foot 4 is an upper companion foot 10, carried on a sleeve 11 slideable on the shank 1, and also having engagement with the spline 6 in order to prevent the rotation of the sleeve on said shank; 75 whereby the vertical alinement of the two feet may be at all times preserved.

A brace 12 is connected between the upper end of the sleeve 11 and the upper foot 10 in order to reinforce the latter. As shown 80 in Figs. 3 and 4 set screws 13 may be employed to bind the sleeves 5 and 11 to the shank 1 after the desired adjustment has been effected. The upper foot 10 is formed with elongated grooves or guideways 14 85 along its opposite longitudinal edges to slidingly receive the overturned flanges 15 on an extension toe 16. As indicated in dotted lines in Fig. 2, this extension toe 16 is capable of being moved back and forth over 90 the guideways 14, and in this manner the length of the upper foot is either enlarged or diminished as required by the width of the boards operated upon, as will be later explained. 95

A bridge 17 is connected between the guideways 14 on the upper part of the extension toe 16 and carries a set screw 18 which is adapted to engage against the upper face of the foot 10 in order to bind the extension toe 16 in the position to which it has been adjusted. 100

As is apparent from Figs. 1 and 2, the outer free end of this extension toe 16 is beveled, as represented at 19, in order to 105 permit the action of the toe as presently explained.

In Fig. 2 there is shown an extension handle 20 having a angled end 21 provided with collars 22 and 23, which are received 110 over the upper end of the shank 1 when the tool is to be used in inaccessible places or at

heights requiring increased reach. A set screw 24 may be carried by one of the collars to bind against the shank 1 in order to hold the extension handle 20 in place thereon. The opposite end of the extension handle 20 is formed with a socket 25 of a size to fit the shank 1, and a fastening means indicated at 26 may be employed to secure the socket in place on the shank.

10 It will be evident that by disengaging the collars 22 and 23 and reversing the extension handle 20, so that the socket 25, which is in axial alinement with the axis of the handle 20, is received over the upper end of the shank 1, the handle 20 will then extend in a straight line with the shank 1. The extension handle 20 therefore may be connected either in the angular relation shown in Fig. 2, or in a straight line with the shank 1, as 15 various uses require.

In use, the tool is applied as shown in Fig. 1 after the nails have been first extracted from the boards shown in dotted lines at 27 by the claw 2, and the first board 25 pried out of place by the chisel edge 3. The board removed by this chisel edge admits the shank 1 to be passed down through the flooring, as shown in Fig. 1, and the lower and upper feet 4 and 10 are then engaged with 30 the next board 27 in the manner indicated. The lower foot 4 engages beneath the board while the upper foot 10 extends above the same, and the extension toe 16 is so adjusted as to bring its beveled edge 19 just beyond 35 the tongue and groove connection between the board worked upon and that next to the same.

The shank 1 is thereupon lifted, or allowed 40 to exert a lever movement with the end 19 of the toe as a fulcrum, and this action will have the effect to lift the board and to withdraw the tongue from the groove without injury thereto. The tool is worked from one end of the board toward the center, and is 45 then carried to the opposite end of the board and from that end likewise worked over to the center of the board. In this manner the board is loosened all along its length gradually and after the center is arrived at, after 50 being worked to from both ends, the board is sufficiently loose to be pried entirely out of place and removed from the ceiling. Subsequent boards are similarly acted upon with like results.

55 In case the boards are of greater width than shown in Fig. 1, the set screws 18 may be loosened and the extension toe 16 set farther out on the upper foot 10 so as to always give the beveled edge 19 a bearing 60 surface on the next board, and in like manner the extension toe 16 may be moved inwardly for boards of lesser width than those shown, but the operation is substantially the same.

65 The upper foot and extension toe are

also capable of a vertical adjustment by loosening the set screw 13 and raising the sleeve 11 on the shank 1, and this adjustment is advantageous when boards of a greater thickness than indicated in Fig. 1 70 are to be operated upon.

The sliding sleeves also admit of bringing the feet closer together where the boards are of lesser thickness.

Either the upper sleeve 11 may be shifted 75 to effect this vertical adjustment, or both the upper sleeve 11 and the lower sleeve 5 may be simultaneously moved as desired.

In dismantling ceiling, the extension handle 20 becomes of great value as it enables 80 the workman to gain access to the ceiling without the necessity of erecting a scaffold. The angular position of the extension handle 20 is found to be most advantageous in the dismantling of wall boards, as it enables the 85 gap between the lower foot 4 and upper foot 10 to be worked up and down the full length of the wall boards, while at the same time placing the operator in a convenient 90 position with respect to the wall and transmitting the force applied in the most effective direction.

The claw 9 is also advantageous in removing the nails from the wall boards, as the sides of the shank 1 would prevent the 95 convenient operation of the lower nail extractor 2 for this purpose.

It will probably be found most convenient to reverse the extension handle 20 from the position shown in Fig. 2 in order to bring 100 same in alinement with the shank 1 when ceiling is to be dismantled, as this gives the workman a greater reach and enables him to pull directly downward on the boards, or to rotate the implement about the extension toe 105 as a center with ease and convenience.

It will be obvious that various modifications might be made in the herein described apparatus, and in the combination and arrangement of parts which could be used 110 without departing from the spirit of my invention; and I do not mean to limit the invention to such details except as particularly pointed out in the claims.

Having thus described my invention what 115 I claim and desire to secure by Letters Patent of the United States is:—

1. A dismantling tool of the character described, including a shank, a lower foot carried by said shank and adapted to be engaged at one side of a board to be removed, and an upper foot movable longitudinally on said shank and adapted to engage at the opposite side of said board, substantially as described.

2. An improved dismantling implement including a shank, spaced feet on said shank adjustable toward and from each other, and one of said feet carrying a fulcrum for the tool, substantially as described.

3. An improved dismantling tool including spaced feet, a shank carrying said spaced feet, and an extension toe carried by and movable with respect to one of said feet and 5 having a fulcrum for the tool, substantially as described.
4. An improved dismantling tool including a shank, spaced feet on said shank, an extension toe carried by and movable with 10 respect to one of said feet, and means to hold the extension toe in adjusted position, substantially as described.
5. An improved dismantling tool including a shank, spaced feet carried on said 15 shank, an extension toe supported by and having a slidable movement with respect to one of said feet, and means for fastening the extension toe in the adjusted position, said extension toe having a fulcrum for the 20 tool, substantially as described.
6. An improved dismantling tool including a shank, spaced feet longitudinally adjustable on said shank, a laterally adjustable extension toe carried by one of said feet, 25 and means for securing the feet and extension toe in adjusted position, substantially as described.
7. An improved dismantling tool including a shank, spaced feet on said shank, and 30 a reversible extension handle having an angled end for connection to said shank, substantially as described.
8. An improved dismantling tool including a shank, spaced feet on said shank, and 35 an extension handle having a socket at one end in axial alinement with the handle and arranged to be received over the end of said shank, said extension handle also having an angled end opposite said socket, with means whereby said angled end may be clamped to 40 said shank for holding the extension handle at an angle to the axis of the shank, substantially as described.
9. An improved dismantling tool including a shank, feet on said shank, one of said 45 feet being adjustable with respect to the other foot, and a reversible extension handle having an angled end adapted to be connected to said shank, substantially as described.
10. An improved dismantling tool including a shank, spaced feet on said shank, one of said feet having guideways, an extension toe having flanges slidingly fitting in said 50 guideways, and means whereby the extension toe may be clamped to said foot when adjusted, substantially as described.
11. An improved dismantling tool including a shank, spaced feet on said shank, one of said feet having guide grooves along its 55 longitudinal edges, an extension toe having flanges at its longitudinal edges bent over into said guide grooves whereby the toe may be slidably supported on said foot, a bridge connected between said flanges and extending over said foot, and means carried by 60 said bridge for binding against said foot to hold the toe in adjusted position, said toe having a beveled outward edge, substantially as described.

EDWARD F. WILKINSON.
